UNITED STATES PATENT OFFICE.

HILMA KORPI, OF KINNEY, MINNESOTA.

DESIGN FOR A COMBINATION BUTTON-HOOK AND BOTTLE-OPENER.

50,949.

Specification for Design.

Patented June 19, 1917.

Application filed April 14, 1917. Serial No. 162,198. Term of patent 7 years.

To all whom it may concern:

Be it known that I, HILMA KORPI, a citizen of the United States, residing at Kinney, in the county of St. Louis and State of Minnesota, have invented a new, original, and ornamental Design for Combination Button-Hooks and Bottle-Openers, of which the following is a specification, reference being had to the accompanying drawing, forming part thereof.

The figure is a perspective view of a combination button hook and bottle opener showing my new design.

I claim:

The ornamental design for a combination button hook and bottle opener as shown.

HILMA KORPI.
